UNITED STATES PATENT OFFICE.

FRANCIS A. WINSLOW, OF CHICAGO, ILLINOIS, ASSIGNOR TO THE WINSLOW BROTHERS COMPANY, OF CHICAGO, ILLINOIS, A CORPORATION OF ILLINOIS.

WINDOW-ADJUSTER.

1,292,978.

Specification of Letters Patent. Patented Jan. 28, 1919.

Application filed September 9, 1916. Serial No. 119,153.

To all whom it may concern:

Be it known that I, FRANCIS A. WINSLOW, a citizen of the United States, residing at Chicago, in the county of Cook and State 5 of Illinois, have invented a certain new and useful Improvement in Window-Adjusters, of which the following is a full, clear, concise, and exact description, reference being had to the accompanying drawings, forming 10 a part of this specification.

My invention provides an adjuster for windows or the like, particularly for holding windows of the type shown and described in my prior application, Serial No. 810,937 15 filed January 8th, 1914, in any desired one of a number of positions. The window described in the above patent is balanced as to weight and is balanced for uniform wind pressures, but sudden gusts of wind sometimes act unequally upon the window sections 20 and cause movement of the same.

My present invention aims to provide simple and convenient means for automatically holding the window shut after the same is 25 moved to the closed position and for holding the window against movement in the desired open position.

The particular form in which I have chosen to embody my invention is neat, inconspicuous, simple and convenient.

In the accompanying drawings I have illustrated one embodiment of my invention.

Figure 1 is a top plan view of the adjuster showing the same attached to the sash and 35 the window frame;

Fig. 2 is a front elevation showing the bracket of the adjuster in section;

Fig. 3 is a side elevation with parts broken away; and

Fig. 4 is a diagrammatic elevation of the window with the adjuster attached.

As shown in Fig. 4, the particular type of window to which my invention is preferably applied comprises a window frame 1 for receiving the two sash members 2 and 3, which are connected to each other through the arm 4 to which each sash is pivoted. The arm 4 is pivoted at its center to the frame 1 and thus the two sash members 2 and 3 may be 45 moved with a combined rotary and sliding movement, as is understood by those skilled in the art.

The adjuster 5, as is shown in Fig. 4 is

connected to the frame and to the lower sash member near the bottom of the window 55 frame 1. The adjuster comprises the stay plate 6 which is secured to the limb 7 of the channel iron which comprises the frame 1.

The stay plate 6 is connected as by means of the screws 8', as shown in Fig. 3, and projects out from the frame 1, having its outer end flared out slightly, as shown at 8 in Fig. 1. The stay plate 6 is also provided with flanges 9 resting against the front of the channel 7 and seating firmly upon the same. 60 The flanges 9 continue around the outer edge of the stay plate 6 except where the same is cut away at 10 (see Fig. 3) to form an engaging notch or socket for the latch member 11 which is pivoted to the bracket 12. The 65 bracket 12 is bolted to the flat outer face of the channel 13 which comprises the frame of the sash member 3 and this bracket projects in a line generally parallel to the stay plate 6. The outer end of the bracket is slotted to 70 receive the latch member 11 and a pin 14 forms the pivots between these two members. The latch member 11 comprises the tongue 15 which fits in the slotted end of the bracket 12 and forms the pivots for this latch member. 75 The member 12 further comprises the tongue 16 which is adapted to drop into the notch 10 by the weight of the latch member when the window is closed and a thumb piece 17 which is adapted to be engaged by 80 the hand of the operator to lift the latch member preparatory to opening the window. The bracket 12 is gained or notched at 18 to render the thumb piece 17 accessible. The 85 bracket 12 carries at its lower end an enlargement 19 which is adapted to receive a bolt 20 which is slidable in and out, as indicated by dotted and full lines in Fig. 2. The bolt 20 is adapted to engage the slots 21, 22, and 23 in order to hold the window in the 90 desired open position. Movement of the bolt 20 is limited by a pin or screw 24 which engages a slot 25 cut in the back or base of the bracket member 12.

The latch member 11 is freely pivoted 100 about the pin 14 and drops of its own weight into the notch 10. The stop 26 on the bottom of the tongue 15 of the latch member 11 prevents excessive movement of the latch member.

105 Downward motion of the latch member 11

is prevented by the top of the bracket member 12.

The adjuster is preferably constructed of brass, bronze, or some other corrosion resisting material, although this is not of the essence of the invention.

In operation it can be seen that the latch member 11 rides upon the top edge of the stay plate 6 until the window is closed, at 10 which time the tongue 16 drops into the notch 10 and holds the window in closed position. The device thus serves the function of a sash lock in holding the window closed. When the latch member 11 is released by 15 raising the thumb member 17, the window may be opened by the usual handles which are provided for this purpose and when the bolt 20 is opposite one of the slots 21, 22, and 23, this bolt may be projected into the 20 slot where it will remain until removed. The bolt 20 thus holds the window in the desired open position.

The outer flared or beveled end of the stay plate 6 provides an incline for automatically restoring the bolt 20 to the open or released position in case the same should accidentally be projected into the path of the stay plate 6 when the window is being closed.

It is apparent from the above that I have 30 provided a simple, neat and convenient device, serving both the purpose of the conventional sash lock and as a means for adjusting and positively holding the window in the desired open position. I do not intend to be limited to the precise details of 35 construction, nor to the exact dimensions and proportions shown and indicated as I consider that it is possible to vary such details without departing from the spirit and 40 scope of my invention.

I claim:

1. In a window adjuster, a stay plate secured to the window frame, a bracket member secured to the frame of the sash, said 45 bracket member having both angular and longitudinal movement in the normal operation of said sash, and means on said bracket member cooperating with said stay plate for holding said bracket member in a predetermined position.

2. In a window adjuster, a stay plate secured to the window frame, a bracket member secured to the frame of the sash, said 55 bracket member having both angular and longitudinal movement in the normal operation of said sash, and means on said bracket member cooperating with said stay plate for holding said bracket and sash in closed position and in a plurality of open positions.

60 3. In a window adjuster, a stay plate projecting out from the window frame, a bracket secured to the frame of the sash, said bracket having a latch member and a bolt member, said stay plate having a notch

adapted to be engaged by said latch member and having sockets or slots adapted to be engaged by said bolt member, said latch and said bolt coöperating with said stay plate member to hold the sash in the closed position or any desired open position. 65

4. In combination, a stay plate having a substantially straight upper edge, a notch at one end of said edge, a plurality of slots in the body of said stay plate, a bracket member having a flat base a latch member pivoted to said bracket member, said latch member being adapted to ride upon the upper edge of said stay plate and to drop into said notch, a bolt member laterally slideable in 70 said bracket member, said bolt member being adapted to engage said slot in said stay plate. 75

5. In combination, a stay plate having a substantially straight upper edge, a notch at one end of said edge, a plurality of slots in the body of said stay plate, a bracket member having a flat base, a latch member pivoted to said bracket member, said latch member being adapted to ride upon the upper edge of said stay plate and to drop into said notch, a bolt member laterally slideable in 80 said bracket member, said bolt member being adapted to engage said slot in said stay plate, 85 said latch member having means for preventing excessive movement of the same and said bolt member having means for preventing excessive movement thereof. 90

6. In combination, a stay plate having a substantially straight upper edge, a notch at one end of said edge, a plurality of slots in the body of said stay plate, a bracket member having a flat base, a latch member pivoted to said bracket member, said latch member being adapted to ride upon the upper edge of said stay plate and to drop into said notch, a bolt member laterally slideable in 100 said bracket member, said bolt member being adapted to engage said slot in said stay plate, 105 said latch member having means for preventing excessive movement of the same and said bolt member having means for preventing excessive movement thereof, said stay plate having means for automatically pushing said bolt back into open or restored position. 110

7. In a window of the austral type, means 115 for holding the sashes in adjusted open position, comprising coöperating latch members fixed to the window frame and one of said sashes at a point removed from the sliding end adapted to interlock at different 120 points to hold the sashes in one of several open positions.

8. In a window of the austral type, means 125 for holding the sashes in adjusted open position and for locking the window shut, comprising coöperating latch members fixed to the window frame and one of said sashes between its ends and adapted to interlock at

different points to hold the window in one of several open positions and to lock the sashes against opening.

9. In a window of the type described, co-
5 operating latch members fixed to the window frame and one of said sashes, adapted to interlock at different points to hold the sashes in one of several open positions, and adapted

when released from open holding relation to automatically lock the sashes against open- 10 ing when the sashes are moved to closed position.

In witness whereof, I hereunto subscribe my name this 2nd day of Sept., A. D. 1916.

FRANCIS A. WINSLOW.
